UNITED STATES PATENT OFFICE.

STANISLAW LANGE, OF PHILADELPHIA, PENNSYLVANIA.

CURTAIN FIXTURE.

Application filed April 1, 1922. Serial No. 543,573.

To all whom it may concern:

Be it known that I, STANISLAW LANGE, a citizen of Poland, residing at Philadelphia, in the county of Philadelphia and 5 State of Pennsylvania, have invented certain new and useful Improvements in Curtain Fixtures, of which the following is a specification.

Among the objects of this invention is that 10 of providing a practical fixture for holding a curtain roll.

Another object is the means whereby the fixture may be applied to the casing of a window and removed at will, without making 15 screwholes or in any way damaging the woodwork of the window.

A further object is the provision of means whereby the fixture may be positioned to suit curtains of any width.

20 These and other like objects are attained by the novel arrangement and combination of parts, hereinafter described and shown in the accompanying drawing, forming a material part of this disclosure, and in 25 which:—

Figure 1 is a side elevational view of the fixture applied to the window casing.

Figure 2 is a perspective view of the fixture.

30 Fig. 3 is a partial sectional detail of the clamping elements.

Referring to the drawing, the numeral 5 indicates the top member of a window casing secured adjacent to frame 6.

35 Secured removably to the upper and lower edges of the casing member 5 are fixture elements 7 and 8, the former being bent to a right angle at its upper end 9, the extremity of which is downturned and bevelled to form

40 a spur 10 extending along the width of the metal plate 7 and adapted to be forced into the casing member.

The adjacent fixture plate 8 is also provided with a right angled bend forming an 45 angular extension 11, and a downwardly depending angular retaining plate 12, having a foot element 13, is secured to the underside of the extension 11 by rivets 14 passing therethru.

50 Formed transversely thru the lower portion of the plate 12 is a slot 15 extending angularly upward from the center of the articulate end of the plate.

An adjustment slot 16 is formed transversely thru the plate 8 and the adjacent outer plate 7 is provided with an annular

opening in line with the slot and adapted to receive a headed stud 17 having a flattened shoulder 18 suited to engage within the slot 16; a screw-threaded portion 19, of the stud 60 extends freely thru the opening in the plate 7, and is threadably engaged thru the bottom of the hollow annular clamp socket 20.

A push button 21, having a flanged shoulder 22, is held within the interior of the 65 socket by inturning or spinning over the outer edge of the socket, forming an abutment for the button shoulder 22, as shown at 23 of Fig. 3.

A coiled spring 24 is interposed between 70 the inner bottom of the socket 20 and the flanged head 22 maintains the button in a normal outward position.

A pin 25 is fixed in the outer portion of the button 21, and extends radially outward 75 in a manner adapted to engage in groove 26, formed diametrically across the face of the socket end 23.

Referring to Figure 3, it will be seen that as the socket 20 is screw-threaded to the 80 stud element 19, and the plate members are drawn in close engagement by the clamping action of the stud head 17 acting thereagainst, the socket functioning as nut, rotating on the stud 19.

To obviate the use of wrenches or screw-drivers when applying, adjusting or removing the fixture, a self contained device is employed consisting of a spring returned button 21 having an extending pin 25 engageable in the slot 26 of the socket, when the button is pressed inward, and in which position the socket may be rotated, the pin acting as a lever while engaged with the socket.

To prevent defacing of the wood-work, when attaching the fixture, cushioning pads 27 and 28 are secured to the corners of the plates coming in contact with the window casing.

While certain preferred embodiments of this device have been shown and described it will be understood that changes in the form, arrangements and details thereof may be made without departing from the scope 105 of the invention as defined in the appended claim.

I claim:—

In a curtain fixture comprising a pair of 110 bent plates attached to a window casing, one of said plates having a vertically disposed slot central therein, said plates being ad-

justably held adjacent one another by a clamp member consisting of a headed stud, a flatted shoulder slidable in the mentioned slot, a threaded end extending freely thru the outer plate and threadably engaging a hollow socket, a push button engaged within said socket, an operating pin fixed in the button, said socket having a slot receptive of

said pin when the button is pushed inwardly, means for turning said socket in either direction, means for maintaining the button in normal outward position, and means for preventing said button from being forced from said socket.

In witness whereof I affix my signature. 15
STANISLAW LANGE.
